CHARLES A. RUSSELL, OF LARAMIE, WYOMING, ASSIGNOR OF ONE-HALF TO WALTER
GEORGE BELL, OF LARAMIE, WYOMING.

SPARK-ARRESTER FOR LOCOMOTIVES.

1,262,098.

Specification of Letters Patent.

Patented Apr. 9, 1918.

Application filed October 29, 1917. Serial No. 199,031.

To all whom it may concern:

Be it known that I, CHARLES A. RUSSELL, a citizen of the United States, residing at Laramie, in the county of Albany and State 5 of Wyoming, have invented certain new and useful Improvements in Spark-Arresters for Locomotives, of which the following is a specification, reference being had to the accompanying drawings.

10 This invention relates to spark arresters for locomotives, and has for its primary object to provide a device adapted to be mounted upon the smoke stack which will arrest the sparks and cinders so that they 15 will not be blown out of the stack by the exhaust.

It is another and more particular object of 20 my invention to provide a spark arrester adapted to be mounted above and in spaced relation to the upper open end of the smoke stack and including a cinder receiving trough constructed to discharge the cinders by gravity into suitable outlets and means 25 for directing the sparks and cinders into the trough but permitting of the free outlet of the smoke.

It is also a more particular object of the 30 invention to provide a spark arrester having means for effecting the separation of the smoke from the cinders, which will not create a back pressure through the smoke stack and thereby interfere with the proper operation of the draft creating exhaust.

The invention also has for a further general 35 object to provide a spark arrester as above characterized which is simple in its construction as well as efficient and reliable in practical operation, and which may be readily applied to the ordinary locomotive 40 smoke stack, without necessitating any structural alteration in the latter.

With the above and other objects in view, my invention consists in the novel features 45 of construction, combination and arrangement of parts to be hereinafter more fully described, claimed and illustrated in the accompanying drawings wherein similar reference characters designate corresponding parts throughout the several views and 50 in which—

Figure 1 is a vertical sectional view illus-

trating the preferred embodiment of my invention applied to the smoke stack of a locomotive;

Fig. 2 is a fragmentary sectional view 55 taken on the line 2—2 of Fig. 1; and

Fig. 3 is a bottom plan view.

Referring in detail to the drawing 5 designates the outer cylindrical body wall of the device the lower portion of which is inwardly inclined as at 6 and integrally connected by means of the substantially cylindrical wall 7 to an inner upwardly and inwardly inclined annular wall 8. The connecting wall 7 forms a cinder receiving 60 trough 9 of substantially circular form in cross section. The walls 6 and 8 at their points of juncture with the walls 7 are spaced apart to afford a continuous annular entrance mouth 10 to the trough 9. The 70 wall 8 in general defines a truncated cone the upper end of which terminates at a point below the straight vertical portion of the body wall 5.

Inwardly projecting lugs 11 are formed 75 on the trough wall 7 and are provided with threaded sockets to receive the threaded upper ends of the supporting rods 12, the lower ends of which are suitably mounted upon the upper end of the smoke stack. It 80 will be noted from a comparison of Figs. 1 and 2 of the drawing that the walls 6 and 8 are directly connected to the circular trough wall 7 only at diametrically opposed points 85 at the front and rear of the device, and from these points, the trough wall 9 is provided 90 with obliquely inclined convergent portions indicated at 13 which extend around each side of the device in a downward direction. These downwardly inclined portions of the 95 trough wall 7 are connected to the inclined walls 6 and 8 by the spaced vertical extensions 6' and 8' of said walls. Thus it will be understood that the entrance throat 10 into the trough gradually increases in depth 95 from the front and rear of the device to the opposite sides thereof. At the juncture of the downwardly inclined converging portions of the cinder trough, suitable drain or discharge pipe connections 14 are provided. 100

At spaced points the wall 18 is provided upon its inner face with lugs 15 having ver-

tical openings extending therethrough to receive the lower ends of supporting rods 16. These rods are provided with stop flanges 17 for engagement upon the upper surface of 5 the wall 8 and nuts 18 are threaded upon the lower ends of said rods. The smoke directing and spark arresting member 19 is in the form of an inverted cone circular in cross section and at its larger upper end is provided with a wide arcuately curved laterally and downwardly extending flange 20. This flange is provided with openings through 10 which the upper ends of the supporting rods 16 are engaged, and additional stop flanges 21 15 are also provided upon the upper ends of the rods to limit the downward movement of the member 19 thereon. The upper ends of said rods are threaded to receive the clamping nuts 22. It is to be noted that the lower 20 edge of the flange 20 is disposed at a point above and in spaced relation to the horizontal plane of the upper edge of the wall 8. Preferably, the flange 20 is provided with 25 equidistantly spaced smoke exit slots 23 extending in parallel relation to the axis of the member 19. Attention is particularly called to the fact that these slots are located at a point in spaced relation to the highest point of the flange 20 and outwardly there- 30 of, while the upper edge of the wall 8 is located in a vertical plane inwardly of this point on the flange 20. The purpose of this relative location of the slots and the upper edge of the wall 8 with respect to the crest 35 of the flange 20 will presently appear.

In the operation of the device, the smoke is forced upwardly through the smoke stack by the exhaust in the usual manner the centrifugal action tending to direct the sparks 40 and cinders outwardly and against the inwardly inclined wall 8 by which they are directed inwardly against the sides of the inverted cone 19. This conical deflecting member directs the products of combustion 45 together with the sparks and cinders upwardly and outwardly against the inner face of the flange 20 and when the sparks and cinders reach the central point or the crest of this flange which as above stated is located outwardly of the inner edge of the 50 wall 8, they will drop downwardly by gravity upon the wall 8 and be outwardly directed by this wall into the trough 9 through the annular mouth 10 thereof. The smoke, 55 is thus freed of the sparks and cinders and finds an exit through the slots 23 and around the lower edge of the flange 20 and passes freely upwardly between said flange and the wall 5. This smoke outlet, has an area 60 which is substantially equal to the internal area of the smoke stack upon which the device is mounted and affords ample space for the escape of the smoke, and effectually pre-

vents back pressure through the smoke stack, which would interfere with the effective operation of the draft exhaust. As hereinbefore stated the sparks and cinders upon entering the trough 9 move by gravity through 65 said trough to points at opposite sides of the device and are discharged at a suitable point 70 through the pipes or connections 14.

From the foregoing description taken in connection with the accompanying drawing, the construction, manner of operation and several advantages of my improved spark 75 arrester will be clearly and fully understood. I have found the device highly effective and reliable in practical operation and have demonstrated that the use thereof will positively prevent live embers and sparks 80 being blown from the stack by the exhaust, thereby obviating liability of structures of a more or less inflammable character which are contiguous to the right of way, being ignited by falling sparks. It is at the same 85 time to be noted that the device presents no impediment or obstruction to the free exit of the smoke. The spark arrester as herein described, may be manufactured in various sizes, and while I have herein referred to the 90 rods 12 for supporting the device upon the smoke stack, it will be apparent that various other alternative supporting means may be employed. In practice, the arrester will be supported above the upper end of the smoke 95 stack at a distance of from one to three feet, which I have found gives the best results. The several parts of the device may be made of pressed steel, malleable iron or other suitable metal. The device as a whole is also of 100 relatively simple construction and may be manufactured at comparatively small cost.

While I have herein described the preferred form, construction and arrangement of the several detail parts of the invention, 105 it is to be understood that the same are susceptible of considerable modification and I therefore reserve the privilege of adopting all such legitimate changes as may be fairly embodied within the spirit and scope of the 110 invention as claimed.

Having thus fully described my invention, what I claim is:—

1. A spark arrester comprising an outer body wall, an inwardly and upwardly inclined annular wall disposed inwardly of and in spaced relation to said body wall, said walls being integrally connected by a wall forming a cinder receiving trough, and means supported upon said inner inclined 115 wall and extending downwardly below the upper edge of the latter wall to direct the sparks outwardly and downwardly into said trough.

2. A spark arrester including a body having inner and outer downwardly converging 120

- annular walls integrally connected in spaced relation to each other at their lower ends by a wall forming a continuous cinder receiving trough, an inverted deflecting cone 5 extending downwardly within said inner annular wall and having an outwardly and downwardly curved flange on its upper end terminating at a point substantially midway between said inner and outer body walls, 10 the crest of said curved flange being located at a point intermediate of the lower edge of said flange and of the upper edge of said inner annular wall.
3. A spark arrester including a body having inner and outer downwardly converging annular walls integrally connected in spaced relation to each other at their lower ends by a wall forming a continuous cinder receiving trough, an inverted deflecting cone 15 extending downwardly within said inner annular wall and having an outwardly and downwardly curved flange on its upper end terminating at a point substantially midway between said inner and outer body walls, 20 the crest of said curved flange being located at a point intermediate of the lower edge of said flange and of the upper edge of said inner annular wall, and means mounted upon said inner body wall for supporting 25 30 the deflecting member.
4. A spark arrester including a body having inner and outer downwardly converging annular walls integrally connected in spaced relation to each other at their lower 35 ends by a wall forming a continuous cinder receiving trough, an inverted deflecting cone extending downwardly within said inner annular wall and having an outwardly and downwardly curved flange on its upper end 40 terminating at a point substantially midway between said inner and outer body walls, the crest of said curved flange being located at a point intermediate of the lower edge of 45 said flange and the upper edge of said inner annular wall, said flange of the deflecting member being provided with a plurality of smoke exit openings.
5. A spark arrester comprising a body having an outer wall, an inner upwardly and inwardly inclined annular wall and a 50 wall integrally connecting said inner and outer walls and forming a cinder receiving trough, a deflecting member mounted upon the inner wall and extending downwardly 55 within the same, said deflecting member having a laterally and downwardly curved flange on its upper end, the crest of said flange being located outwardly of the vertical plane of the upper edge of said inner annular wall and the lower edge of said 60 flange terminating at a point above the horizontal plane of the upper edge of said annular wall and the lower edge of said flange terminating at a point above the horizontal plane of the upper edge of said annular wall, said flange being provided with a plurality of smoke exit openings.
6. A spark arrester comprising a body having an outer wall, an inner upwardly and inwardly inclined annular wall and a wall integrally connecting said inner and outer walls and forming a cinder receiving trough, a deflecting member mounted upon the inner wall and extending downwardly within the same, said deflecting member having a laterally and downwardly curved flange on its upper end, the crest of said flange being located outwardly of the vertical plane of the upper edge of said inner annular wall and the lower edge of said flange terminating at a point above the horizontal plane of the upper edge of said annular wall, said flange being provided with a plurality of smoke exit openings.
7. A spark arrester comprising a body having an outer wall, an inner upwardly and inwardly inclined annular wall and a wall integrally connecting said inner and outer walls and forming a cinder receiving trough, a deflecting member mounted upon the inner wall and extending downwardly within the same, said deflecting member having a laterally and downwardly curved flange on its upper end, the crest of said flange being located outwardly of the vertical plane of the upper edge of said inner annular wall and the lower edge of said flange terminating at a point above the horizontal plane of the upper edge of said annular wall, said flange being provided with a plurality of smoke exit openings.
8. A spark arrester comprising a body having an outer annular wall, an inner upwardly and inwardly inclined wall and a trough wall integrally connecting the spaced lower edges of said walls, said trough having downwardly inclined converging sections at the opposite sides of said body and a drain pipe connected to said sections at their juncture, and a deflecting member supported above said inner inclined body wall and having a downwardly and outwardly curved flange terminating on a plane above the upper edge of said inner body wall and operating to direct the sparks and cinders downwardly upon said wall and thence into the trough and to direct the smoke outwardly between said flange and the outer body wall.
9. A spark arrester comprising a body having an outer annular wall, an inner upwardly and inwardly inclined wall and a trough wall integrally connecting the spaced lower edges of said walls, said trough having downwardly inclined converging sections at the opposite sides of said body and a drain pipe connected to said sections at their juncture, and a deflecting member sup-

porting said inner inclined body wall and having a downwardly and outwardly curved flange terminating on a plane above the upper edge of said inner body wall and operating to direct the sparks and cinders downwardly upon said wall and thence into the trough and to direct the smoke outwardly between said flange and the outer

body wall, said flange being provided with a plurality of smoke exit openings.

In testimony whereof I hereunto affix my signature in the presence of two witnesses.

CHARLES A. RUSSELL.
